UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

HEMMER FOR SEWING MACHINES.

Application filed July 27, 1918. Serial No. 246,986.

To all whom it may concern:

Be it known that I, ALBERT H. DE VOE, a citizen of the United States, residing at Westfield, in the county of Union and State 5 of New Jersey, have invented certain new and useful Improvements in Hemmers for Sewing Machines, of which the following is a specification, reference being had therein to the accompanying drawings.

10 This invention relates to attachments for sewing machines commonly known as hemmers. It is an improvement upon the construction of hemmer shown in my copending application Serial No. 797,946, filed October 29, 1913.

15 It aims to provide simple and inexpensive means for displacing from across the line of seam formation an arbor which would otherwise obstruct the closing or complete stitching of endless hems. It also aims to insure 20 uniformity in the distance the stitches are laid from the inner edge or the edge fold of a hem throughout the formation of an endless seam. It aims still further to provide 25 conveniently operable and simple devices permitting a hemmer to be thrown out of operation.

The hemmer of the present invention comprises in its preferred embodiment, scroll 30 and arbor sections the former of which is stationary relative to the line of seam formation and is provided with an upwardly directed lip for guiding the inner edge or edge-fold of the hem immediately before it reaches 35 the needle, and the latter (arbor) of which is fixed to one end of a lever fulcrumed on a horizontal axis below the cloth-plate about which axis it may be swung to remove it from an obstructing position, in the line 40 of seam formation in order to complete the stitching of endless hems without stopping the machine. The hemmer is secured to an apron which covers and conceals the stitch-forming mechanism beneath the cloth-plate 45 and the apron, which is hinged to the bed-plate, is moved about a horizontal axis away from the cloth-plate to throw the hemmer out of operation, thus making the machine more convenient for straightaway stitching.

50 The invention is illustrated in the accompanying drawings in which Fig. 1 is a plan view of the hemmer applied to the end of the work-plate of a sewing machine. Fig. 2 is a front elevation of the same. Fig. 3 is a side elevation of the same. Fig. 4 is a per-

spective of the arbor section of the hemmer. Fig. 5 is a cross section of the scroll section of the hemmer on line A—B, Fig. 1, showing in front elevation a lip thereon. Fig. 6 is also a cross-section on the line A—B, Fig. 60 1, through both sections of the hemmer with a piece of work in the condition it assumes in its passage through the hemmer.

In the drawings the invention is shown applied to a machine of the chain-stitch type 65 in which the needle 1 cooperates with a looper 1' supported and actuated beneath the cloth-plate 2 which is provided with slots 3 for a feed-dog 4 and with an elongated opening 5 for the needle. The looper-operating 70 mechanism may be of any suitable type such as that shown in my Patent No. 1,385,047, dated March 30, 1920. The cloth-plate 2 is cut away as indicated at 6 to receive the upper flanged portion 7 of an apron 8 which is 75 secured by the screws 9 to an arm 10 on one end of a pin 11 fitted within a sleeve 12 which is journaled in a boss 13 integral with the bed-plate 14 of the machine. The sleeve 12 has a collar 15 integral therewith through 80 which is threaded a screw 16 clamping the pin 11 fast to the sleeve and confining the apron 8 against lateral movement in either direction. In a recess 17 provided in the collar 15 the end of a pin 18 is adapted to 85 seat, under the propulsion of a spring 19 socketed in an adjustment screw 20, when the apron 8 occupies the position shown in Fig. 3, covering and protecting the looper and feeding mechanism beneath the cloth-plate 90 2 of the machine.

To the flanged portion 7 of the apron is adjustably secured by the screw and slot connection indicated at 21, an angular plate having a horizontal portion 22 and vertical 95 portion 23, the latter of which depends in front of a portion of the apron 8. To the angular plate 22—23 the scroll section 24 of the hemmer is soldered or otherwise suitably fixed. This scroll section 24 is of the 100 form shown in cross section in Fig. 5 in which clearly appears an upwardly directed lip 25 which serves to direct the inner edge or edge-fold of the hem a uniform distance to one side of the needle, the distance being 105 varied by the adjustment afforded by the slot-and-screw connection 21 to suit the work being done. An edge-guide 26 is formed on the angular plate 22—23 to one side of the needle and it merges into the de- 110

livery end of the concave wall 27 of the scroll section of the hemmer.

The arbor section 28 of the hemmer is of the shape and form shown in the drawings 5 and interfits with the scroll section 24 to define a channel for folding the material into a hem. The edges of the scroll and arbor sections meet so as not to break the continuity of the work-guiding channel, 10 their line of cleavage being indicated at 29. The arbor section 28 is secured to one end of a lever 30 which is fulcrumed intermediate its ends on a screw 31 threaded into the vertical portion 23 of the angular plate, 15 a spring washer 32 being interposed between the head of the screw 31 and the lever to frictionally retain it in any position into which the lever may be displaced by manual manipulation of its handle or operating end 20 33. To retain the arbor-section 28 in its normal hemming position, shown in Figs. 1, 2 and 3, a resilient arm 34 is secured at 35 to the angular plate 22—23 with a pin 36 on its free end disengageably seated in a 25 correspondingly shaped recess in the lever 30.

With the described construction the operator may move the arbor section of the hemmer to the dotted line position shown in 30 Fig. 2 and then conveniently position the work within the scroll section of the hemmer after which the arbor section is easily moved to the position shown in solid lines in Fig. 2. If the work be endless (circular 35 or tubular) in character, the machine may be started and operated continuously until the initial stitches approach the receiving end of the hemmer. At this time the operator by lifting the end 33 of the lever 40 supporting the arbor section may move the arbor from its obstructing position within the hem and in the line of seam formation to a non-obstructing position to one side thereof, thus allowing the complete stitching 45 of an endless hem without stopping the stitch-forming mechanism. If it is not desired to use the hemmer the operator may pull the apron 8 down upon its hinged connection with the bed-plate of the machine. 50 Having thus set forth the nature of the invention, what I claim herein is:—

1. In combination with a sewing machine having a needle and cloth-plate, a hemmer having separable scroll and arbor sections 55 the former of which embraces the latter and defines therewith a channel for folding under the margin of material, a lever fulcrumed below the cloth-plate and supporting said arbor section, said arbor section being 60 arranged in front of the needle across the line of seam formation.

2. In combination with a sewing machine having stitch-forming mechanism including a needle and cloth-plate, a hemmer 65 having a scroll section pivoted below the

cloth-plate for movement about an axis transverse the line of feed, an arbor section also pivoted below the cloth-plate for movement into and out of cooperative relation with the scroll section, and movable about 70 an axis parallel to the line of feed.

3. In combination with a sewing machine having stitch-forming mechanism including a needle and cloth-plate, a hemmer having a scroll section pivoted below the cloth- 75 plate, an arbor section pivoted also below the cloth-plate and to said scroll section, said pivots being transverse to one another.

4. In combination with a sewing machine having stitch-forming mechanism including 80 a needle and cloth-plate, a hemmer having a scroll-section pivoted below the cloth-plate, an arbor-section also pivoted below the cloth-plate, said pivots being transverse to one another.

5. In combination with a sewing machine having stitch-forming mechanism including a needle and a cloth-plate, a hemmer having separable scroll and arbor sections the former of which partly embraces the latter to 90 define a channel for folding under the margins of material, a lever supporting said arbor section and fulcrumed below the cloth-plate for permitting manual shifting of said arbor section away from the scroll 95 section to allow complete stitching of endless circular hems without stopping the operation of the stitch-forming mechanism, and means for holding said arbor section in cooperative relation with said scroll section. 100

6. In combination with a sewing machine having stitch-forming mechanism including a needle and cloth-plate, a hemmer having separable scroll and arbor sections the former of which partly embraces the latter 105 to define a hem forming channel, a lever supporting said arbor section and fulcrumed intermediate its ends below the cloth-plate, one end of said lever being free and conveniently accessible for manual manipulation to shift the arbor section relative to the scroll section.

7. In combination with a sewing machine having upper and lower stitch-forming mechanism, a cloth-plate below which is located the lower stitch-forming mechanism, a hemmer having pivotally connected scroll and arbor sections, an apron supporting the sections and covering the lower stitch-forming mechanism, a pivot for said apron below 120 said cloth-plate, and means for holding the apron raised in covering position with the hemmer in substantially the plane of the cloth-plate.

8. In combination with a sewing machine 125 having upper and lower stitch-forming mechanism, a cloth-plate below which is located the lower stitch-forming mechanism, a hemmer having pivotally connected scroll and arbor sections, an apron support- 130

ing the sections and covering the lower stitch-forming mechanism, a pivot for said apron below said cloth-plate, and yielding means for holding the apron raised in covering position and the hemmer in substantially the plane of the cloth-plate.

9. In combination with a sewing machine having stitch-forming mechanism and a cloth-plate, a hemmer having a relatively fixed scroll section provided at one side thereof with an upwardly directed lip adjacent the line of seam formation, an arbor section in normal position partly embraced by the scroll section and located across the line of seam formation in rear of the lip on the relatively fixed scroll section, and a lever supporting said arbor section and fulcrumed beneath the cloth-plate.

10. In combination with a sewing machine having stitch-forming mechanism and a cloth-plate, a hemmer having a relatively fixed scroll section provided at one side thereof with an upwardly directed lip adjacent the line of seam formation, an arbor section in normal position partly embraced by the scroll section and located across the line of seam formation in front of the lip on the relatively fixed scroll section, a lever supporting said arbor section and fulcrumed beneath the cloth-plate, and a hinged support for said fulcrum, the axis of the support's hinge being arranged transverse the axis of the lever's fulcrum.

11. In combination with a sewing machine having stitch-forming mechanism and a cloth-plate, a hemmer having relatively movable scroll and arbor sections the former of which has a concave fold-guiding wall, an angular supporting plate for said sections with substantially horizontally and vertically disposed portions, an edge guide on said angular plate to one side of the line of seam formation and forming substantially a continuation of the concave fold-guiding wall of the scroll section, a lip on the scroll section defining with the edge guide a permanent channel for guiding a hem to the stitch-forming mechanism, a lever carrying said arbor section fulcrumed to the vertical portion of said angular supporting plate, an apron covering part of the stitch-forming mechanism beneath the cloth-plate, said angular plate being secured to said apron, means supporting said apron and permitting it to be shifted away from the cloth-plate and permitting the hemmer carried thereby to be thrown out of operative position, and a detent cooperating with said lever to hold the arbor section in cooperative relation with the scroll section.

12. An under hemmer attachment for sewing machines having stationary and movable hem forming sections one of which

is pivoted to the other, an arm for moving the pivoted section, and a spring detent carried by the stationary section for engaging the arm to restrain accidental displacement of the pivotal section when it is in normal hemming position, the axis of the pivoted connection between the sections being horizontal and parallel to the line of seam-formation.

13. In a sewing machine having stitch-forming mechanism including a needle and a cloth-plate, separable scroll and arbor sections, a member movably supporting the arbor section, a member supporting said scroll section, a pivot between said members whose axis is parallel to the line of seam formation, and a hinged support for one of said members, the axis of the hinge being arranged transverse the axis of the pivot between the members supporting the sections of the hemmer.

14. In combination with a sewing machine having stitch-forming mechanism including a needle and cloth-plate, a hemmer having a scroll-section and an arbor-section, one of said sections being pivoted below the cloth plate and movable about an axis extending substantially in the general direction of the line of feed.

15. In combination with a sewing machine having stitch-forming mechanism including a needle and cloth-plate, a hemmer having a scroll-section and an arbor-section, the arbor-section being pivoted below the cloth-plate and movable about an axis extending in substantially the general direction of the line of feed.

16. In combination with a sewing machine having stitch-forming mechanism, an apron pivotally mounted on the machine, a hemmer having scroll and arbor sections, a plate adjustably secured to the apron and sustaining the scroll and arbor sections in operative position with the stitch-forming mechanism.

17. In combination with a sewing machine, an apron pivoted to the machine, a hemmer comprising scroll and arbor sections, a plate adjustable on the apron and sustaining one of the sections and pivot means for sustaining the other section on the plate.

18. In a sewing machine having a cloth-plate, an apron hinged below the cloth-plate, a hemmer comprising scroll and arbor sections, means for adjustably sustaining one of said sections on the apron and pivot means for sustaining the other section on the first said means.

In testimony whereof, I have signed my name to this specification.

ALBERT H. DE VOE.
